UNITED STATES PATENT OFFICE

128,293

DESIGN FOR A BOTTLE HOLDER

Drexel T. Carlson, Kansas City, Mo., assignor to
C. Earl Hovey, Kansas City, Mo., as trustee

Application April 2, 1941, Serial No. 100,097

Term of patent 7 years

To all whom it may concern:

Be it known that I, Drexel T. Carlson, a citizen of the United States, residing at Kansas City, in the county of Jackson and State of Missouri, have invented a new, original, and ornamental Design for a Bottle Holder, of which the following is a specification, reference being had to the accompanying drawings, forming a part thereof.

Fig. 1 is a top plan view of the bottle holder, showing my design.

Fig. 2 is an edge elevational view thereof.
Fig. 3 is an inverted plan view thereof; and
Fig. 4 is an enlarged plan view of a fragment of the bottle holder.

I claim:

The ornamental design for a bottle holder, as shown.

DREXEL T. CARLSON.
